(57) **CLAIM**

The ornamental design for a spot light, as shown and described.

DESCRIPTION

FIG. 1 is a front perspective view of a spot light showing my new design;

FIG. 2 is a rear perspective view thereof;

FIG. 3 is a front elevational view thereof;

FIG. 4 is a rear elevational view thereof;

FIG. 5 is a right-side elevational view thereof;

FIG. 6 is a left-side elevational view thereof;

FIG. 7 is a top plan view thereof;

FIG. 8 is a bottom plan view thereof;

FIG. 9 is an enlarged front perspective view thereof taken along a line 9-9 in FIG. 1;

FIG. 10 is another top plan view thereof showing an alternate configuration in which a portion of the design is rotated to the left; and,

FIG. 11 is another top plan view thereof showing an alternate configuration in which a portion of the design is rotated to the right.

The broken lines shown in the drawings illustrate portions of the spot light that form no part of the claimed design.

1 Claim, 6 Drawing Sheets
